CLAIM

The ornamental design for a pedestal, as shown and described.

DESCRIPTION

FIG. 1 is a perspective view of the pedestal of the present invention;

FIG. 2 is a perspective view from another angle of the pedestal of FIG. 1.

FIG. 3 is a side, elevational view of the pedestal of FIG. 1, the opposite side view being a mirror image.

FIG. 4 is a front elevational view of the pedestal of FIG. 1.

FIG. 5 is a rear elevational view of the pedestal of FIG. 1; and,

FIG. 6 is a top plan view of the pedestal of FIG. 1.

No view of the bottom of the pedestal of the present invention is provided since the bottom of the pedestal, when in use, is not seen.

1 Claim, 3 Drawing Sheets
